OR D 12,845

DESIGN FOR FRINGE.

Design No. 12,845, dated April 4, 1882.

UNITED STATES PATENT OFFICE.

GEORGE S. HENSEL, OF PHILADELPHIA, PENNSYLVANIA.

DESIGN FOR FRINGE.

SPECIFICATION forming part of Design No. 12,845, dated April 4, 1882.

Application filed February 21, 1882. Term of patent 3½ years.

To all whom it may concern:

Be it known that I, GEORGE S. HENSEL, a citizen of the United States, residing in the city and county of Philadelphia, State of Pennsylvania, have invented and produced a new and original Design for Fringe, of which the following is a specification, reference being had to the accompanying photographic illustration, forming part thereof.

10 My invention consists of a design for fringe, the pendants of which are adapted to ornament the face of the head of the fringe.

A represents the head of the fringe, which may be of the order of gimp or flat fabric.

15 B represents a series of pendants which are

connected to the head, each pendant being formed of a length of chenille or other suitable material bent or doubled, as at a, the bend being on the face of the head, thus serving to ornament said face.

20

I claim—

The design for fringe, consisting of a lead having doubled pendants, the bends thereof being on the face of the head, substantially as above set forth.

GEO. S. HENSEL.
